(57) **CLAIM**

The ornamental design for an hourglass shaped packaging element, as shown and described.

DESCRIPTION

FIG. 1 is an upper, front, right perspective view of a first embodiment of an hourglass shaped packaging element, showing my new design;

FIG. 2 is an upper, rear, right perspective view thereof;

FIG. 3 is a front view thereof;

FIG. 4 is a rear view thereof;

FIG. 5 is a left view thereof;

FIG. 6 is a top view thereof;

FIG. 7 is a bottom view thereof;

FIG. 9 is an upper, front, right perspective view of a second embodiment of an hourglass shaped packaging element, showing my new design;

FIG. 10 is an upper, rear, right perspective view thereof;

FIG. 11 is a front view thereof;

FIG. 12 is a rear view thereof;

FIG. 13 is a right view thereof;

FIG. 14 is a left view thereof;

FIG. 15 is a top view thereof; and,

FIG. 16 is a bottom view thereof.
